DESIGN FOR A CASEMENT FOR Portholes OR THE LIKE

Robert W. Rowland, Newark, N. J.

Application September 18, 1942, Serial No. 108,272

Term of patent 7 years

To all whom it may concern:

Be it known that I, Robert W. Rowland, a citizen of the United States, residing in the city of Newark, county of Essex, and State of New Jersey, have invented a new, original, and ornamental Design for a Casement for Portholes or the like, of which the following is a specification; reference being had to the accompanying drawing, forming a part thereof.

In the drawing,

Fig. 1 is a front elevational view of a casement for portholes or the like, showing my new design,

Fig. 2 is a side elevational view thereof,
Fig. 3 is a rear elevational view thereof, and
Fig. 4 is a fragmentary vertical sectional view
taken on line 4—4 of Fig. 1.

The characteristic features of my design are
shown in full lines in the drawing.

I claim:

The ornamental design for a casement for
portholes or the like, as shown and described.

ROBERT W. ROWLAND.
